DESIGN FOR AN AIRPLANE WIND WHEEL TOY

Tegran M. Samour, Stoneham, Mass.

Application April 8, 1937, Serial No. 68,626

Term of patent 3½ years

To all whom it may concern:

Be it known that I, Tegran M. Samour, a citizen of the United States of America, residing at Stoneham, in the county of Middlesex and State of Massachusetts, have invented a new, original, and ornamental Design for an Airplane Wind Wheel Toy, of which the following is a specification, reference being had to the accompanying drawing, forming part thereof.

Fig. 1 is a plan view of an airplane wind wheel toy showing my new design;

Fig. 2 is a side elevation of Fig. 1; and

Fig. 3 is a front view on a reduced scale, looking to the left of Fig. 2.

I claim:

The ornamental design for an airplane wind wheel toy, as shown.

TEGRAN M. SAMOUR.
